[57] **CLAIM**

The ornamental design for a packaged air compressor set, as shown and described.

DESCRIPTION

FIG. 1 is a perspective view taken from top, front and right end of a packaged air compressor set showing my new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a left side elevational view thereof;

FIG. 7 is a right side elevational view thereof; and

FIG. 8 is a reduced top, front and left end perspective view thereof, showing the cover in an open position.

FIG. 1

FIG. 2

FIG. 3

FIG. 4
